MACHINE FOR LAYING PAPER MULCH

Filed Jan. 29, 1930

Raphael Metetal ^{Inventor}

By

S. C. Thomas ^{Attorney}

UNITED STATES PATENT OFFICE

RAPHAEL METTEAL, OF PLYMOUTH, MICHIGAN

MACHINE FOR LAYING PAPER MULCH

Application filed January 29, 1930. Serial No. 424,381.

My invention relates to a horse-drawn machine for laying paper mulch, shown in the accompanying drawings and more particularly described in the following specification 5 and claims.

The primary object of the invention is to provide a machine of simple, inexpensive construction, which is adapted to unroll paper mulch upon a previously prepared soil while 10 concurrently scraping aside a relatively thin layer of the surface soil from the path of the mulching paper;—the soil upon the passage of the machine, automatically falling and overlapping the edges of the paper which has 15 been previously unrolled upon the ground without the employment of mechanical means for turning the soil over the marginal edges of the paper as the machine is drawn in a forward direction by horse or other power.

20 A further object of the invention is to provide means whereby the machine may be adjusted for laying different widths of mulching paper.

25 A further object of the invention consists in providing means whereby the roll of paper may rest directly upon the ground, that it may follow the contour of the ground and be always in contact with its surface.

30 A further object of the invention is to provide means for carrying an additional roll or rolls of mulching paper, to avoid the necessity of returning to a storehouse for supplies should the roll in use be exhausted during the mulching operation in the field.

35 Another feature of the invention consists in a pair of adjustable shield-scrapers, assembled in V-shaped relation,—fitted with adjustable tail pieces, which normally are substantially parallel with the ends of the mulching roll under working conditions. The V-shaped shield-scrapers are adapted to force to each side a relatively thin layer of the surface soil as the machine is driven in a forward direction,—the soil being supported from 40 falling into the path of the mulching paper by the walls of the shield-scraper and the adjustable tail pieces hinged to the end of the latter. Upon the passage of the machine, the soil scraped to each side of the surface, afterwards covered by the mulch, automatically

falls over and upon the marginal edges of the previously laid mulch paper, thus securing the latter against displacement by wind or other natural causes.

With the foregoing and other objects in view which will appear as the description proceeds, the invention further resides in the combination and arrangement of parts and in the details of construction hereinafter described and claimed, it being understood that changes may be made in the precise embodiment of the invention herein disclosed without departing from the spirit of the same.

In the drawings accompanying this specification:

Figure 1 is a perspective view of the machine laying a paper mulch, indicating its adjustable wedge-shaped members in the act of scraping off a thin layer of the surface soil from a previously prepared bed prior to covering the marginal edges of the paper with the soil as the machine unrolls the mulching paper upon the bed.

Figure 2 is a transverse sectional view through the mulching paper and ground on which it is laid, showing the soil overlapping the edges of the paper.

Referring now to the letters of reference placed upon the drawings:

A denotes a frame, comprising a longitudinal member A¹ having a depending bracket A² at its forward end to which is hinged a pair of adjustable shield-scraper plates B.

C indicates a bracket for supporting a wheel D,—adjustably secured to the longitudinal bar A¹ of the frame by a bolt C¹, extending through a slot in the bracket.

E denotes a hook secured to the end of the longitudinal bar for supporting a single-tree.

B¹ B² are adjustable tail-pieces, hinged to the rear end of the shield-scraper plates.

F, F are adjustable supporting arms for carrying a roll of mulching paper, pivoted at F¹ to the shield-scraper plates. F² F³ are U-shaped guides overlapping the supporting arms F, F, to limit the up and down movement of the latter. The arms F, F are curved slightly adjacent the hinge connection between the scraper plates B and tail-pieces B¹

and at each end are bent at right-angles to the body of the bar to provide trunnions F^3 for receiving and supporting the roll G of mulch paper, mounted thereon.

5 H is a divided transverse bar, the outer ends of which are bent at substantially right-angles to provide a footing for attachment to the tail pieces B^1 . H^a is an auxiliary bar connecting the divided bars H together, 10 through the bracket fixtures K , bolted to the transverse member A^2 at the rear end of the longitudinal member A^1 of the frame.

L L denotes handles bolted at L^a , to the longitudinal member A^1 of the frame.

15 M and M^1 are cross-bars to maintain the handle bars in spaced relation. N N are upright members bolted at their upper ends to the handle bars and at their lower ends to the transverse member A^2 at the end of the 20 longitudinal member A^1 of the frame.

P are cross-braces secured to the upright members N , N to stiffen the handle bars.

25 R is a bracket to support one end of an extra roll of paper, the other end of the roll being lodged in the crotch formed by the handle bars L .—or an additional bracket R may be attached to the longitudinal member of the frame to assist in supporting the roll if preferred.

30 Having now indicated the several parts by reference letters, the construction and operation of the device will be readily understood.

The soil is first thoroughly prepared for 35 planting, and should be soft and in proper workable condition.

The roll of mulching paper G is supported on the inwardly directed trunnions of the adjustable bars F ,—the latter being free to swing up and down to permit the roll of paper 40 per to rest directly upon the surface of the soil, so that upon unrolling it may follow the contour of the ground.

The machine may be drawn by one or more horses over the surface of the soil, the latter 45 being scraped slightly toward each side of the bed by the forward movement of the adjustable wedge-shaped shields, thus providing a substantially level path for the mulching paper as it is unwound upon the ground 50 by the advancement of the machine over the latter.

The machine in its progress over the ground while scraping its upper surface forces the soil outwardly causing it to follow 55 the sides of the scraper-shield until it reaches the end of the tail pieces,—the latter being substantially parallel with the ends of the roll of mulching paper,—whereupon 60 the soil losing the support of the shields,—automatically falls over and upon the marginal edge of the paper, covering the latter and protecting it from being disturbed by winds or other natural causes, without the necessity of employing other means to turn the 65

soil upon the edges of the paper, or to cut a furrow in the soil to receive its edges.

It will be apparent that by this arrangement, a hand wheel hoe may be run between and over the edges of the mulching paper 70 without disturbing the latter, eliminating all hand hoeing. It will also be seen that the soil between the strips of mulching paper being higher than the beds covered by paper 75 will result in all rainfall flowing toward the beds.

After laying the mulching paper, holes may be punched through the paper as suitable intervals to receive the plants or seeds as desired.

Having thus described my invention, what I claim is:

1. A machine for unrolling and laying mulching paper comprising a frame; a pair of shield-scraper members secured at their 80 forward ends to the frame, and extending rearwardly in spaced wedge-shaped relation to each other, whereby they are adapted for scraping a relatively thin layer of surface soil to each side of the machine and to automatically deposit same upon the marginal edges of a mulching paper; and means for holding a roll of mulching paper at the rear of said shield-scraper members, the roll being in contact with the surface of the soil, whereby as the machine is driven in a forward direction, the mulching paper is unrolled upon the ground and its marginal edges covered by the soil delivered at the rear of the scraper-shield members due to the passage of the 90 machine.

2. A machine for unrolling and laying mulching paper, comprising a frame; a pair of adjustable shield-scraper members hinged at their forward ends to the frame, extending 100 rearwardly in spaced wedge-shaped relation to each other, whereby they are adapted for scraping a relatively thin layer of surface soil to each side of the machine to be automatically deposited upon the marginal edges of a mulching paper; and adjustable means for holding a roll of mulching paper at the rear of said shield-scraper members in contact with the surface of the soil, whereby as the machine is driven in a forward direction, the mulching paper is unrolled upon the ground and its marginal edges overlapped by the soil delivered at the rear of the scraper-shield members upon the passage of the 105 machine.

3. A machine for unrolling and laying mulching paper, comprising a frame; a pair of adjustable shield-scraper members hinged at their forward ends to the frame extending rearwardly in spaced wedge-shaped relation to each other, whereby they are adapted for scraping a relatively thin layer of surface soil to each side of the machine and to automatically deposit the same upon the marginal edges of a mulching paper; and a pair 110

115

120

125

130

of automatically adjustable bars respectively pivoted at their forward ends to the adjustable shield-scraper members, with inwardly directed trunnions at their rear ends for holding a roll of mulching paper in contact with the surface of the soil, whereby as the mulching paper is unrolled upon the ground by the forward movement of the machine, its marginal edges are overlapped by the soil delivered at the rear of the scraper-shield members.

4. A machine for unrolling and laying mulching paper, comprising a frame; a pair of adjustable shield-scraper members hinged at their forward ends to the frame, extending rearwardly in spaced wedge-shaped relation to each other; a pair of tail pieces hinged to the rear ends of said shield-scraper members adapted to overlap the ends of a roll of mulching paper; and adjustable means for holding a roll of mulching paper between said tail pieces in contact with the surface of the soil, whereby as the machine is driven in a forward direction, the mulching paper is unrolled upon the ground and its marginal edges overlapped by the soil delivered at the rear of the tail pieces upon the passage of the machine.

5. A machine for unrolling and laying mulching paper, comprising a frame; a pair of adjustable soil-scraper members, hinged at their forward ends to the frame extending rearwardly in spaced wedge-shaped relation to each other; a pair of tail plates respectively hinged to the rear ends of said soil scraping members; a divided spacing bar provided with foot pieces secured to said tail pieces, a pair of bracket fixtures secured to the frame, adapted to receive and support the opposing ends of the divided spacing bar; an auxiliary spacing bar connecting the divided transverse bar and supported by the bracket fixtures, and a pair of inclined handle bars secured at their forward ends to a longitudinally extending member of the frame, a pair of upright members respectively bolted to said handle bars and to a transverse member of the frame; and a plurality of cross bars and braces connected with said upright members adapted to stiffen and give rigidity to the handle bars.

6. A structure as specified in claim 1, in combination with a wheel supporting bracket fixture, adapted to be adjustably secured to the forward end of the frame of the machine; and means for adjustably securing said fixture to the frame.

In testimony whereof, I sign this specification.
